UNITED STATES PATENT OFFICE.

EDWIN ANDERSON McKOY, OF NEW ORLEANS, LOUISIANA.

TURPENTINE-CUP.

No. 906,057.

Specification of Letters Patent.

Patented Dec. 8, 1908.

Application filed June 10, 1907. Serial No. 378,203.

To all whom it may concern:

Be it known that I, EDWIN A. McKOY, a citizen of the United States, residing at New Orleans, in the parish of Orleans and State of Louisiana, have invented certain new and useful Improvements in Turpentine-Cups; and I do hereby declare the following to be a full, clear, and exact description of the invention, such as will enable others skilled in the art to which it appertains to make and use the same.

This invention relates to improvements in means for gathering turpentine from trees and particularly to the construction of the apron upon which the sap falls and from which the cup is suspended and into which the sap is directed from the apron.

The main object of the invention is to provide an apron of improved construction so shaped at its lower edge as to provide means for suspending a cup therefrom.

With these and other objects in view, the invention comprises certain novel constructions, combinations and arrangements of parts, as will be hereinafter fully described and claimed.

In the drawings:—Figure 1 is a view in perspective of the improved cup and apron. Fig. 2 is a view in perspective of a slightly different embodiment of the invention as applied to the apron. Fig. 3 is another slightly different embodiment of the improved apron.

Like characters of reference designate corresponding parts throughout the several views.

The improved apron forming a part of the present invention comprises a substantially plain body portion 10 having upwardly extending converging flanges 11 formed at its opposite ends and either with or without the concave upper edge 12, as shown, such concave edge being desirable in the majority of cases to conform to the curvature of the tree but not being essential to the successful and satisfactory embodiment of the invention.

At the lower edge a pair of longitudinally disposed extensions 13 are provided which said extensions may be formed as shown in Fig. 1 by simply producing longitudinally disposed slots 14 or, as shown in Fig. 2, by producing the slots 14 and turning down the flange 15 or, as shown in Fig. 3, by employing a wire or like device and rolling the edge as 16 about the wire with the opposite extremities of the wire extending longitudinally beyond the ends of the apron at its lower edge.

For use in association with the apron above described a cup or receptacle 17 is employed having upstanding arms 18 carried thereby and formed in any approved manner as integral with or rigidly secured to the receptacle, and provided with any approved form of means for engaging with the extensions 13, as the hooks 19 shown, the specific hook shown in Fig. 1, such hook being preferably employed from economy, but not from necessity.

It will be understood that the upper edge of the apron is seated in the turpentine bearing tree in the usual manner by forming an incision in the tree and inserting the upper edge of the apron therein with the apron disposed preferably at an inclination with the shorter edge the lower and with the cup or receptacle 17 suspended therefrom and below the apron in position to receive drippings from the edge.

What I claim is:—

1. In a device of the class described, an apron comprising a substantially plain body portion, converging upstanding flanges formed at opposite ends of and terminating at a point upon the body of the apron, extensions formed at the opposite ends of the shorter side of the apron, and a receptacle provided with means adapted to engage the extensions.

2. In a device of the class described, an apron comprising a substantially plain body portion, extensions formed at the opposite ends of the lower side of the apron produced by the interposition of longitudinally extending slots, and a receptacle provided with means adapted to enter the slots and engage upon the extensions.

3. In a device of the class described, an apron comprising a substantially plain body portion, a flange formed upon the lower side of the apron, said apron provided with slots projected from opposite ends substantially at the curvature between the body and the flange.

4. In a device of the class described, an apron comprising a substantially plain body portion, a flange formed upon the lower edge of the body portion, and extensions provided upon the opposite ends of the flange by the interposition of cut away portions of the apron from opposite ends.

5. In a device of the class described, an apron provided with projections formed at the extremities of the lower edge by the in-

terposition of cut away portions of the apron at opposite ends.

6. In a device of the class described, an apron comprising a substantially plain body 5 portion having a concave upper engaging edge, converging flanges formed upon the opposite ends of the apron and terminating at a point upon the body of said apron short of the lower longitudinal edge, and extended 10 engaging members formed adjacent the

lower longitudinal corners by the interposition of slots projected substantially parallel with the lower longitudinal edge.

In testimony whereof I affix my signature in presence of two witnesses.

EDWIN ANDERSON McKOY.
